ASSIGNEES TO AMERICAN ELECTRICAL HEATER COMPANY, OF DETROIT, MICHIGAN,
A CORPORATION OF MICHIGAN

ELECTRIC IRON

Application filed October 19, 1931. Serial No. 569,802.

This invention relates to electrically heated laundry irons and has as one of its objects to improve generally irons of the above type by simplifying the construction of the several parts involved and by reducing the number of such parts to a minimum.

Heretofore considerable inconvenience has been experienced in the manufacture of laundry irons owing to the fact that certain purchasers insisted upon an iron equipped with a heel stand capable of supporting the iron in an upright position when not in use, while other purchasers preferred an iron without a heel stand. Accordingly, in order 10 to secure the approval of both of the aforesaid groups of purchasers, certain manufacturers have considered it necessary to produce two different series of irons, one with and one without the heel stand. The manufacture of two different types of irons is 20 obviously objectionable not only since it materially increases the cost of handling and manufacture of the irons, but appreciably retards production thereof.

25 The present invention contemplates eliminating the foregoing objections as well as satisfying both the aforesaid groups of purchasers by providing a heel stand capable of being readily attached to and removed 30 from the iron in an exceedingly simple manner within the skill of any user. The above arrangement obviously permits manufacturing the iron and heel stand separately and in addition offers the possibility of selling the heel stand as an attachment for the 35 iron.

Another object of this invention is to provide an arrangement of the type specified above wherein the heel stand is held in assembled relation with the iron by fastening means which, in addition to performing the above operation, also functions to secure the insulator blocks and casing therefor as a unit to the iron.

45 A further advantageous feature of this in-

vention resides in the provision of a heel stand which is extremely light in construction so as not to appreciably add to the weight of the iron when in assembled relation therewith.

A still further object of this invention consists in extending the electrical cord or conductor through the insulator block casing in such a manner that the same will not interfere with supporting the iron in an upright 50 position by the heel stand.

The foregoing as well as other objects will be made more apparent as this description proceeds, especially when considered in connection with the accompanying drawing, 55 wherein:

Figure 1 is a fragmentary perspective view of an electrically heated laundry iron equipped with a heel stand constructed and secured in place in accordance with the present invention;

Figure 2 is a side elevational view of the iron showing the same supported in its upright position by the heel plate;

Figure 3 is a fragmentary sectional side 70 elevational view of the iron shown in Figures 1 and 2;

Figure 4 is a fragmentary sectional view taken substantially on the line 4-4 of Figure 2.

75 For the purpose of illustration, we have shown our invention as employed upon an electric laundry iron of the type shown in the drawing having a base or heat distributing plate 10, a pressure plate 11 secured to the base plate 10 and a heating element 12 disposed between adjacent faces of the two aforesaid plates. As is usually the case in irons of the type illustrated herein, the operation of the heating element 12 is accurately 80 controlled by means of a thermostatic switch 13 located in close proximity to the base plate 10 for receiving the heat mainly therefrom. The heating element 12 and thermostat 13 are protected and concealed by means of a 85

removable cover 14 having side and end walls seated upon the base plate 10 and secured in position thereon by means of a single fastener element 15. The handle 16 may be of the conventional design having front and rear frame members 17 and 18, respectively, projecting upwardly from the cover and having the upper ends thereof secured in any suitable manner to the adjacent ends of a suitable non-metallic grip 19.

Electric energy is supplied to the heating element 12 through the thermostatic switch by means of a pair of terminal contact elements 20 and 21 having the lower ends electrically connected to opposite sides of the circuit extending through the heating element and switch and having the upper ends extending through an elongated opening 22 formed in the cover 14 in rear of the handle 16. The upper portions of the terminal members extending through the cover are connected to suitable flexible electrical conductors which in turn are adapted to be connected to a source of electric energy. The connecting portions of the conductors and terminal contact members are protected and insulated from each other by means of an insulator block 23 formed of a pair of separable sections 24 and 25. As will be observed from Figure 3, the sections 24 and 25 cooperate with each other and with a second insulator block 26 closing the opening 22 in the cover to conceal the electrical connections aforesaid and insulate the same from metallic contact with the remaining parts of the iron.

The insulator block 23 is in turn concealed by means of a metallic housing 27 having the marginal edges thereof engaging the portions of the cover surrounding the elongated opening 22 therethrough and having an opening 28 in the upper wall thereof to provide for the passage of the flexible conductors therethrough. The sections 24 and 25 of the insulator block 23 are clamped in assembled relation with each other within the housing 27 and the latter is secured to the iron by means of a single fastener element designated generally herein by the reference character 29. The fastener element 29 comprises a bolt 30 having a head 31 engaging the inner surface of the handle frame member 18 and having a threaded shank 32 extending through aligned openings formed in the handle frame section 18, opposite front and rear walls of the housing 27 and insulator block sections 24 and 25. The threaded shank portion 32 of the bolt is of such length as to extend through all of the aforesaid parts and to project a substantial distance rearwardly from the rear wall of the housing 27 for receiving a suitable clamping nut 33. The above arrangement is such that by merely removing the nut 33 from the rear end of the bolt, the latter may be removed from engagement with the housing 27 and sections

24 and 25 of the block, with the result that the aforesaid parts may be disassembled exposing the electrical connection between the flexible conductors and terminal contact members.

As previously stated, it is one of the principal objects of this invention to provide a removable heel stand for the iron operable when in assembled relation therewith to support the same in an upright position. The heel stand provided herein is designated generally in the several views by the reference character 34 and as will be presently described, is readily removably attached to the rear end of the iron in a position to permit supporting the iron in the position shown in Figure 2 when the same is not in use. The heel stand 34 is preferably of one piece construction comprising a substantially U-shaped portion 35 extending rearwardly from the rear end wall of the cover at substantially right angles thereto in spaced relation to the base plate 10 of the iron. The rear end or base of the U-shaped portion 35 terminates in a forwardly and upwardly extending portion 36 having the forward end thereof adapted to abut the adjacent surface of the end wall of the cover 14. The rear connecting ends of the portions 35 and 36 extend for substantially the full width of the iron so as to provide an ample support for the latter when in its upright position and the metal connecting the said portions is preferably curved as indicated in the several views so that there will be no danger of the same marring the surface of the support when in engagement therewith. In the interest of reducing the weight of the heel stand to the minimum, the same may be formed from sheet metal and the portion 36 may be provided with a transversely extending opening 37 therethrough. Formed integral with and extending upwardly from the forward edge of the portion 36 is a suitable finger 38 terminating at the upper edge thereof in a return-bent curved portion 39 adapted to cooperate with the rear ends of the portions 35 and 36 to support the iron in the position shown in Figure 2. The finger 38 is formed on the portion 36 intermediate the side edges thereof and assumes a position adjacent the rear wall of the housing 27 opposite the rear handle frame portion 18 when the stand is in assembled relation with the iron.

The heel stand above described is positioned upon the rear wall of the cover 14 by means of a pair of cooperating engaging shoulders formed on the legs of the U-shaped portions 35 and the rear wall aforesaid of the cover. In detail, the front marginal edges of the legs of the U-shaped portion 35 are provided with ears 40 adapted to extend through corresponding openings 41 in the rear wall of the cover. As will be observed from Figure 3, the ears 40 are curved downwardly sufficiently to prevent any tendency for the same to become acci-

dentially disengaged from the openings 41 when the stand is secured in place on the iron. The stand 34 is positively and readily detachably secured in place by means of the fastener element 29 hereinbefore set forth. As shown particularly in Figure 3, the length of the fastener element is so determined that the rear end thereof extends through a suitable opening formed in the finger 38 prior to receiving the nut 33, with the result that the latter, in addition to clamping the various parts of the iron hereinbefore enumerated, also serves to secure the heel stand in place.

With the construction as previously described, it will be apparent that the heel stand, in addition to being relatively light in weight and inexpensive to manufacture, may be readily removed from or attached to the heater by merely manipulating the nut 33 on the bolt 30. For example, assuming that the heel stand is in assembled relation with the iron and it is desired to remove the same, the nut 33 is merely disengaged from the bolt 30 permitting the stand to in effect pivot about the ears 40 and thereby disengage the finger 38 from the end of the bolt 30. The ears 40 may then be removed from the slots 41 in the cover and the nut 33 replaced upon the end of the bolt 30 whereupon the iron is in condition for use without the heel stand. On the other hand, in the event it is desired to assemble the heel stand with the iron, the nut 33 is merely removed from the bolt and the ears 40 engaged within the openings 41 in the rear wall of the cover whereupon the stand is pivoted about the ears to extend the free end of the bolt within the opening formed in the finger after which the nut may be reassembled with the bolt to secure the stand in position. Thus, it will be seen that the stand may be removed from or assembled with the iron without interfering with the position of any of the remaining parts thereof.

Since, as previously stated, the finger 38 assumes a central position in rear of the iron, the opening 28 in the casing 27 through which the conductors extend is offset relative to the center of the housing so as to permit the conductors to extend at an angle from the housing. As will be observed from Figure 1, the foregoing arrangement is such as to provide for locating the flexible conductor in spaced relation to the finger 38 and thereby minimize any tendency for the conductors to obstruct tilting of the iron to the position shown in Figure 2.

What we claim as our invention is:

An electric iron having a cover, terminal contact elements projecting through the cover, a sectional insulator block enclosing the projecting portions of the contact elements, a housing enclosing said block, a heel stand for supporting the iron in a substantially upright position, a fastener element

carried by the iron and having a threaded shank portion extending through the housing, insulator block sections and a portion of said heel stand, and a clamping nut adapted to be threaded upon the outer end of said shank for clamping the parts through which said threaded shank extends in assembled relation with the iron.

In testimony whereof we affix our signatures.

FRANK KUHN.
